CLAIM

The ornamental design for a sprinkler, as shown and described.

DESCRIPTION

FIG. 1 is a top perspective view of a sprinkler, according to our new design;

FIG. 2 is a bottom perspective view of the sprinkler shown in FIG. 1;

FIG. 3 is a front side elevational view of the sprinkler shown in FIG. 1;

FIG. 4 is a rear side elevational view of the sprinkler shown in FIG. 1;

FIG. 5 is a top side view of the sprinkler shown in FIG. 1; FIG. 6 is a bottom side view of the sprinkler shown in FIG. 1;

FIG. 7 is a left side elevational view of the sprinkler shown in FIG. 1;

FIG. 8 is a right side elevational view of the sprinkler shown in FIG. 1; and,

FIG. 9 is a top perspective view of the sprinkler shown in FIG. 1, illustrated together with an unclaimed, optional support member.

The broken lines in the figures are included for the purpose of illustrating unclaimed portions of the sprinkler and an unclaimed, optional support member and form no part of the claimed design.

1 Claim, 9 Drawing Sheets
